KNIFE, FORK, AND SPOON SET

Filed April 1, 1946

UNITED STATES PATENT OFFICE

2,439,882

KNIFE, FORK, AND SPOON SET

Raymond R. Beddoe, Toledo, Ohio

Application April 1, 1946, Serial No. 658,832

6 Claims. (Cl. 30—147)

1

This invention relates to a device for packaging a set of eating utensils and particularly to a fork, knife and spoon holder forming a part of the equipment in the kit of a camper, soldier, traveler or the like.

It is an object of this invention to produce a new and improved container for holding a fork, knife and spoon in a manner which militates against their relative movement, separation, loss or impairment in view of the rigidity with which they are held in the assembled position.

Another object is to produce a knife handle attachable jacket in which the nested fork and spoon having tapered handles, may be readily mounted to comprise a neat and compact package. Tensioning means are provided for wedging the inserted utensils thereby substantially to eliminate rattling noises and uncontrolled movements of the utensils resulting from the vibrations or jars incident to travel.

A further object is to produce a case readily formed from a strip of sheet metal, plastics or other formable materials which may be attached to the handle of a knife to comprise a jacket in which the other eating utensils may be readily mounted during their non-use forming an attractive, low cost and useful addition to the equipment of a camper, traveler or military personnel.

Other objects and advantages of the invention will become evident from the following description, and for purposes of illustration but not of limitation, embodiments of the invention are shown on the accompanying drawings, in which

Figure 1 is a perspective view of a case attached to the handle of a knife and holding a nested fork and spoon;

Figure 2 is a transverse sectional view of the holder and attaching means showing the fork and spoon in the mounting and mounted position;

Figure 3 is a cross sectional view taken substantially along the line 3—3 of Figure 1;

Figure 4 is an enlarged fragmentary view of another form of the holder;

Figure 5 is a sectional view of the case illustrated in Figure 1, but secured to the knife handle by rivet means; and

Figure 6 is an enlarged fragmentary view of still another form of a utensil carrying case.

It may be readily understood that the random placement of the metallic forks, knives and spoons in a traveler's kit, not infrequently results in their misplacement, loss or damage. Often the sharp edges of the knife or fork tines

2

are found to be a detriment to other articles contained in the kit, and in addition, the vibrations and jars incident to travel cause the metallic elements repeatedly to contact each other producing bothersome rattling noises as well as impairing the finish of the metallic elements. It is, therefore, expedient to provide a case 10 with which the knife 11, fork 12 and spoon 13 may be rigidly packaged during non-use to militate against their loss or impairment, as well as to dispose the sharp edges or tines of the utensils in a manner which prevents damage to adjacent articles. In the illustrated embodiment of this invention, use is made of forks and spoons having tapered handles, such as to form a neck portion adjacent the bowl and an outwardly tapering portion adjacent thereto. It is to be understood that handles tapered from the end may also be used as will be hereinafter explained.

20 The case 10 is easily formed, as by folding, from a rectangular strip of sheet metal, plastics, or other rigid but resilient materials. The strip is folded to comprise a substantially rectangular open end cylinder having side walls 14 and 15, a front wall 16 and a rear wall 17 formed by the lateral edge portions which do not meet, thus to form an intermediate intervening slot 20.

25 Since the substantially rectangular case 10 is of a contour which fits comfortably into the grasp of a hand, it is convenient to attach the case 10 with the handle 21 of the knife 11 thereafter to comprise a part of the knife handle. In the embodiment of the invention illustrated in Figures 1 to 3, a length of wire 22 is tightly coiled about 30 the knife handle 21 juxtaposed to the front wall 16 of the case 10 combining them into a unitary structure subsequently to be used as such.

35 A pair of aligned openings 23 in the upper rearward portion of the side walls 14 and 15 receive hooked ends 24 and 25 on opposite ends of a wire spring clasp 26. As viewed in Figures 1 and 2, the clasp 26 comprises a pair of laterally spaced V-shaped sections 25. Integrally connecting the upper rearwardly extending legs 26' is a horizontally disposed cross arm 27, the lower legs 28 each being integrally attached to their respective hooked ends 24 and 25 by means of laterally extending arms 29 and 30 and intermediate curvilinear portions 31 and 32 which are contoured 40 in a manner enabling the wire clasp to be rocked about the registered hooked ends.

45 In the position of non-use, the spaced V-shaped sections 25 are angularly disposed so that the span between the apices 32 is slightly less than 50 the span between the ends of their respective

legs. In addition, the V-shaped members are laterally spaced so that the span between the apices 32 is greater than the width at the neck of the insertable utensils but less than the width of adjacent handle portions.

In use, the wire clasp 26 is pivoted about its hook flanges to the rearward position as illustrated by the broken lines in Figure 2. The cleaned fork 12 and spoon 13 are then inserted handle first into the case until the narrow neck portion lies within the swinging arc of the apices 32. The position of the fork and spoon at this point is illustrated by the broken lines in Figure 2. The wire clasp 26 is then rocked to its upright position until the cross arm 27 is stopped by the back of the rearmost utensil, at which time the V-shaped sections substantially fit about the side walls of the fork and spoon. Subsequent movement of the enclosed fork and spoon effects the engagement between the wider handle portions and the V-shaped members flexing same in the outward direction, as by a wedging action, whereby the V-shaped members tensionally grasp the enclosed utensils. In this manner, the knife and fork are positively held until external forces are applied to lower the utensils relieving the tensioned wire clasp so that it can be rocked away from the upper opening enabling the utensils to be removed.

The embodiment of the invention illustrated on Figure 5 is essentially the same as that previously described, the difference residing in the means by which the case 10a is secured to the knife handle 21a. In this instance, the wire coil 22 is replaced by a pair of rivets 33 which rigidly and substantially permanently secure the case 10a to the handle 21a.

Another form of the invention, illustrated in Figure 4, comprises a case 10b similar to that previously described and attachable to the knife handle in any suitable manner. Modification resides in the means for wedging the fork and spoon in the packaged position. In this instance, a pair of spaced horizontal prongs 34 and 35 are reciprocably slidable in apertures 36 and 37 in the rear wall 17b of the case. The ends extending beyond the rear wall are integrally connected by a horizontal arm 38, thus to comprise a U-shaped spring wire clasp 39, the inner ends of which are flanged at 40 to prevent the removal of the clasp from the case 10b.

The span between the prongs 34 and 35 is arranged to be greater than the width of the utensils at their neck portion, but less than the width of their adjacent handle portions. Thus, in use the clasp is slidably displaced to the rearward position of adjustment as illustrated by the broken lines in Figure 4, freeing the upper opening of the case 10b for free access thereto. The fork and spoon are inserted, handle first, until the narrow neck portions are in alignment with the prongs of the wire clasp. The clasp is then manually forwardly displaced until the flanged ends 40 abut the inner wall of the front wall 16b of the case. Subsequent movement of the enclosed utensils in the upward direction effects engagement between the handle portions of greater width and the resilient prongs, flexing them outwardly. Thus tensioning forces are created which hold the engaged utensils in the mounted position and also prevent subsequent movement of the wire clasp. The packaged position is readily maintained until external forces are applied to modify the arrangement.

Still another form of wire clasp 41 suitable for

use with cases of the type described, is illustrated in Figure 6. In this instance, a U-shaped spring wire member 41 is pivotally mounted in a bearing sleeve 43 secured to an upper intermediate edge of the tube wall 16c. The cross arm 44 of the U-shaped member is substantially entirely enclosed by the sleeve 43, the outwardly extending arms 45 and 46 being curvilinear having their ends extending in the direction towards each other.

5 The span between the arm ends is selected to be greater than the width of the neck portion of the insertable utensils, but less than the width of the adjacent handle portions.

10 Thus the arms 45 and 46 may be pivoted in the upward direction freeing the upper opening for insertion of the cleaned utensils therethrough. When the utensils have been lowered to the point where the neck portions are within the arc of the wire clasp 41, the latter is rocked to the horizontal position substantially enclosing the utensil handles. Subsequent movement of the utensils in the upward direction effects the engagement between the utensil handle portion of greater width with the arms of the wire clasp 25 41 flexing same in the outward direction, thus to generate holding forces such as previously described in connection with the other embodiments.

15 Description has been made to a jacket having a spring clasp adapted to hold a fork and spoon. It is to be understood that other utensils may be substituted therefor and that additional implements having the desired handle contour may be readily packaged in the container described.

20 35 It is manifest that I have produced an exceedingly simple jacket for attachment on to a knife handle for packaging other eating implements in a manner which eliminates rattling noises, loss or damage to the utensils during transportation from place to place. The low cost device provides a neat and compact addition to the kit of a camper or soldier and in view of its forming a part of the knife handle, the items comprising the pack equipment are thereby not increased.

25 45 It is to be understood that other changes in details of construction, arrangement and operation may be effected without departing from the spirit of the invention especially as defined in the appended claims.

50 50 What I claim is:

1. A holder for forks and spoons having tapered handles comprising an elongate tube having open ends and adapted to be attached to the handle of a table knife and receive a nested fork and spoon, and means on said tube adapted to fit the narrow portions of the fork and spoon handles and to wedge against the wider portions of such handles upon their relative shifting movement with the tube.

60 60 2. A holder for forks and spoons having tapered handles comprising a substantially rectangular open end tube folded from a sheet metal strip and adapted to be attached to the handle of a table knife, and means on said tube adapted to fit the narrow portion of the fork and spoon nested in the tube and to wedge against the wider portions of such handles upon their relative shifting movement with the tube.

65 70 3. A holder for forks and spoons having tapered handles comprising a sheet metal tube having an open end and adapted to receive a nested fork and spoon, means attaching said tube to the handle of a table knife, and means on said tube movable between two positions of adjustment adapted in one position to free the open end

of the tube and in the other position to fit over the narrow portion of the nested fork and spoon handles and to wedge against the wider portions of such handles upon their relative shifting movement with the tube.

4. A holder as claimed in claim 3, in which the movable wedging means comprises a spring wire clasp pivotally mounted in the upper portion of the tube, and having spaced V-shaped members adapted in the other position of adjustment to fit about the narrow portion of nested fork and spoon handles and to be flexed in response to the wedging action of the wider portion of such handles upon their relative shifting movement with the tube.

5. A holder as claimed in claim 3, in which the movable wedging means comprises a U-shaped member slideable transversely through spaced openings in one wall of the tube and having the free arms extending transversely of the

upper portion of the tube, and abutments on the ends of said arms militating against their disengagement from the tube.

5 6. A holder as claimed in claim 3, in which the movable wedging means comprises a sleeve secured to an upper edge of the tube, and a U-shaped spring wire clasp pivotally mounted in said sleeve enabling the free arms of said clasp to extend transversely of said tube in the other position of adjustment.
